UNITED STATES PATENT OFFICE.

FRANK W. BEBERDICK, OF WEST HOBOKEN, NEW JERSEY.

DESIGN FOR A COAT-PATTERN.

SPECIFICATION forming part of Design No. 30,212, dated February 14, 1899.

Application filed November 8, 1898. Serial No. 695,897. Term of patent 14 years.

To all whom it may concern:

Be it known that I, FRANK W. BEBERDICK, a citizen of the United States, residing at West Hoboken, in the county of Hudson and State 5 of New Jersey, have invented and produced a new and original Design for a Coat-Pattern, of which the following is a specification, reference being had to the accompanying drawing, forming part thereof.

10 The drawing represents in plan view a pattern of one side and half of the back of the coat, showing my new design, and it will be understood that the other side and half of the back are the same.

15 As shown in the drawing, the leading or material feature of my design consists in the part A, forming one side and half the front, and the part B, forming half of the back, and in the particular shape or contour given to 20 the upper edge or ends of these parts. From the point a^3 the edge of the part A is slightly curved inwardly and then outwardly and downwardly to the point a' , forming the compound-curved line a^2 . At the point a' the edge 25 is curved sharply and extends downwardly to the point a^8 , forming the straight line a , which is inclined downwardly and inwardly, corresponding substantially to the hypotenuse of a right-angle triangle. At the point 30 a^8 the edge is again curved sharply and then extends in a straight horizontal line, forming the bottom edge of the part A.

The upper portion of the part A is cut away to form part of the neck-opening, said 35 part of said opening being represented by the inwardly and upwardly curved line a^4 , extending to the point a^5 , from which last-named point the edge extends in a slight downward and then upward curve to the point a^7 , forming 40 the compound-curved line a^6 . The point a^7 is located below the point a^5 and slightly above a horizontal plane passing through the point a^8 . The compound-curved line a^6 represents the shoulder line or seam. The edge 45 of the upper portion of the part A extends downwardly and inwardly from the point a^7 in a curve deviating only slightly from a straight line to the point C^3 , from which point

the said edge is curved in a small semicircle to the point C^3 . From the point C^3 the edge 50 extends downwardly and is slightly curved outwardly and then inwardly to the point C^4 , from which point the said edge extends downwardly in a straight line to the bottom of the garment.

55 The outer edge of the part B extends in a straight line b^5 from its extreme upper point b^4 to the extreme lower point b^6 . The inner edge of the part B extends in a straight line from the bottom thereof to the point C^4 , coinciding with the corresponding part A. From the point C^4 the edge of the part B extends upwardly and is slightly curved outwardly and then inwardly until it meets the point C^3 of the part A at the point b^8 , thus forming a 60 double-curved opening b^7 , tapering to a meeting-point at the upper and lower ends thereof. From the point b^8 the edge of the part B extends upwardly, curving first inwardly and then extending in an inclined straight line to 65 the point b , which is opposite but slightly below the point a^7 of the part A and separated therefrom by a narrow space b^9 . From the point b the edge of the part B extends upwardly in a straight but sharply-inclined line 70 to the point b^2 , thus giving the shape of an obtuse angle to the point b . The upper edge of the part B extends from the point b^2 in a downward curve to the point b^4 , which point is located slightly below the point b^2 , but on 75 the same horizontal plane as the point a^5 of the part A.

Having fully described my invention, I claim as new and desire to secure by Letters Patent—

80 The design for a coat-pattern as herein shown and described.

In testimony that I claim the foregoing as my invention I have signed my name, in presence of the subscribing witnesses, this 29th 85 day of October, 1898.

FRANK W. BEBERDICK.
